E. E. Overholt
ATTORNEY.

UNITED STATES PATENT OFFICE.

HERBERT V. W. SCOTT, OF PATERSON, NEW JERSEY.

WARP-THREAD PLATE.

Application filed April 21, 1924. Serial No. 708,046.

To all whom it may concern:

Be it known that I, HERBERT V. W. SCOTT, a citizen of the United States, residing at Paterson, in the county of Passaic and State 5 of New Jersey, have invented certain new and useful Improvements in Warp-Thread Plates, of which the following is a specification.

My invention relates to warp thread plates 10 for textile machines; and is not only used for threading-in a warp, but in many cases the threads continue to run through the plate after both the warp and the plate are placed in the machine. It is not only used 15 in jacquard machines, but is also used for making of warps in any textile machine where a warp is used, as for instance, in warp knitting machines, broad silk looms, carpet looms, etc., etc.

20 In textile warping, the yarn is first wound on spools, and a large number of these spools are placed on a jack or creel. The ends of the threads from these spools are threaded through the holes of the warp thread plate 25 which is placed directly in front of the warping mill. Then as the threads are run through the plate onto the mill, they are gauged by the lay-out of the plate holes to conform with the machine gauge or cloth 30 count desired. Hence the plates vary in shape according to the machine with which they are to be used and the number of threads per inch desired. The plate shown in the drawings has 168 holes laid out in 35 six rows on a four inch plate; others might have an equal number of holes laid out in four rows on a six inch plate; while others might have a total of, say, only 80 holes, etc.

The object in view is to provide a plate 40 that will prevent the yarn from being cut by any rough edge or surface.

I have found out by experience that silk running at a high speed through holes in a metal plate will cut the metal regardless 45 of its hardness and the grooves and irregularities thus formed, will in turn, abrade and cut the threads.

Minor objects of the invention will appear in the subjoined description. 50 The invention consists in the construction and arrangement of the parts, and the method of assembling the same and securing them in rigid relation to each other, as will

be hereinafter described and claimed, reference being had to the accompanying drawings, in which:—

Fig. 1 is a plan view of a plate embodying my improvement; and, Fig. 2 is a broken section, on an enlarged scale, showing one form of eyelet or bushing as it appears embedded in the plate.

The numeral 1 indicates the plate, which is provided with a plurality of suitably arranged holes 2; and these holes are provided in turn with eyelets or bushings 3 to take up 65 the wear.

I have found in practice that porcelain is an admirable material to use in making these bushings, because of its great smoothness and great resistance to wear; but I do 70 not limit myself to the use of any one material, either hard or soft, for these eyelets or bushings, using whatever material may be found most desirable to meet any given case, since my device is not limited to the 75 silk industry, but as already stated, is used with any textile machine whatsoever where warps are used.

The eyelets are secured in the plate in any ordinary or preferred manner. In practice 80 I have found that mould casting is usually satisfactory. The small eyelets are placed on pins inside the mould, and the molten metal, or alloy, poured in.

These eyelets or bushings are made in any 85 desired form, that illustrated in Fig. 2 of the drawings being a good form. In this form the eyelet is provided exteriorly with an annular swell 3^a, so that when the molten metal hardens around it, the eyelet will be 90 very firmly held in the plate, which is comparatively thin.

Whenever it is deemed necessary to do so, a little antimony may be added to the metal or alloy (from which the plate is more often 95 made), to cause the metal as it cools to contract around the eyelets, and in that way grip them very tightly.

The addition of the swell 3^a to the eyelet gives it great strength for its size.

To those skilled in the art, the value of my improvement will be immediately apparent, since in an all-metal plate, however hard it may be, the strands of silk will soon cut the eyes, as stated above; while an all- 105 porcelain plate is very brittle, and conse-

2
quently easily broken; but with my arrangement any suitable material, either metallic or non-metallic, may be used for the plate.

Having now described my invention, what
5 I claim as new and desire to protect by Letters Patent is:—

1. In a device of the character described, a plate formed from molten metal by casting, and having wear eyelets previously 10 formed of a different material, said eyelets being arranged in position conforming to the configuration of the plate to be formed, and cast in the plate simultaneously with its formation, the molten metal being poured 15 around them; whereby the complete eyelet plate is formed at a single operation, and the plate and eyelets are from a practical point of view integral in formation.

2. In a device of the character described, 20 a plate formed from molten metal by casting, and having wear eyelets previously formed of a different material, said eyelets being arranged in position conforming to the configuration of the plate to be made, 25 and cast in the plate simultaneously with its formation, the molten metal being poured around them; whereby the complete eyelet plate is formed at a single operation,

the eyelets being arranged between the planes formed by the opposite sides of the 30 plate, whereby not to project beyond said planes.

3. In a device of the character described, a plate formed from molten metal by casting, and having wear eyelets previously 35 formed of porcelain, said eyelets being arranged in position to conform to the configuration of the plate to be formed, and cast in the plate simultaneously with its formation, the molten metal being poured around 40 them in the plate, whereby to utilize the shrinkage of the metal in cooling to rigidly secure the eyelets in the plate without the use of cement, the eyelets being of a length equal to the thickness of the plate with their 45 open ends flush with the sides of the plate; whereby to provide a plate of practically integral construction without projections on either of its faces.

4. In a device of the character described, 50 the combination with a plate having openings therein for the threads, of bushings cast in said openings, said bushings being exteriorly provided with annular swells.

In testimony whereof I affix my signature.
HERBERT V. W. SCOTT.
